UNITED STATES PATENT OFFICE.

FRANK R. CLARK, OF CINCINNATI, OHIO, ASSIGNOR TO THE CINCINNATI SAND BLAST COMPANY, OF CINCINNATI, OHIO, A CORPORATION OF OHIO.

METHOD OF PRINTING ON TARLATAN AND OTHER LIKE FABRICS.

1,106,364.

Specification of Letters Patent. Patented Aug. 11, 1914.

Application filed August 7, 1911. Serial No. 642,673.

To all whom it may concern:

Be it known that I, FRANK R. CLARK, a citizen of the United States, and a resident of the city of Cincinnati, in the county of 5 Hamilton and State of Ohio, have invented a certain novel and useful Method of Printing on Tarlatan and other like Fabrics, of which the following is a full, clear, and exact description, reference being had to the 10 accompanying drawing, forming part of this specification.

The object of my invention is to provide a method for printing signs, pictorial illustrations and the like in one or a plurality of 15 colors, particularly upon light, flimsy and open-work fabrics such as tarlatan and the like, where the fabric is of such a character that any of the ordinary and usual methods of printing in colors are not available.

20 When it is sought to print by mechanical means upon such fabrics as tarlatan, by reason of the open mesh, the ink inevitably spreads and blurs when ordinary methods are employed, while with my improved 25 method, designs in various colors may be clearly and sharply imprinted without the slightest tendency of the ink to blur or run.

To carry out my process, a plate is first prepared for each color, with the design 30 etched or cut into the surface of the plate in the same order in which it is to appear when imprinted on the goods. In preparing the plate, I prefer to employ a plate of glass upon which the design is etched in the usual 35 way with acid.

Where imprints are to be made in a number of colors, the etched design for the particular color is then filled with ink of the desired colors, and a dry impression is taken 40 from this plate upon a sheet of suitable paper by pressing the paper upon the plate to take up the ink. In this way the imprint will appear upon the paper impression sheet in reverse in raised characters of the 45 thickness of the ink on the etched plate. In order to transfer the design from the paper impression sheet to the fabric, I prefer to employ the apparatus illustrated in the drawing, in which—

50 Figure 1 is a side elevation. Fig. 2 is a front elevation.

The fabric to be printed, in the present instance, tarlatan, is mounted on a roll 1 which is journaled in a frame-work consisting of diagonally disposed cross bars 2, 2,

and side bars 3, 3, for each side, and with plates 4, 4, connecting the side bars so as to form a solid and substantial box frame, of the proper width for the fabric and preferably square in shape. Trunnions 5, 5, are 60 provided for the box frame, by which it is mounted to rotate freely in side standards 6, 6. In order to lock the box frame while printing, however, a lock bar 7 is provided pivoted to one of the standards 6 and arranged to engage between the lugs 8, 8, on the four sides of the box frame, so that the four faces of the box may be in turn locked in a vertical front position for the printing. The plates 4, 4, forming the sides of the box 70 frame are open at the corners, and in these corner spaces guide rolls 9, 10, 11, 12 and 13 are mounted. At one of the corners, the two guide rolls 12 and 13 are provided. The web of tarlatan 15, or other fabric, from the roll 1 is passed over the roll 13 and around the box frame over the guide rolls 9, 10, 11 and 12 and back to the storage roll 14, which is mounted in the opposite cross bars 2, 2, of the box frame. This storage roll is provided 75 with the hand crank 16 so that the fabric when printed as hereinafter described may be wound up on the storage roll. Both the supply roll 1 and the storage roll 14 are provided with pawls 17, 18, and ratchets 19, 80 20, to prevent any back movement of the fabric and to hold same taut, the pawls being held in place in engagement with the ratchet by the springs 21, 22, respectively.

In order to prevent the freshly printed 90 fabric from blurring as it is wound up on the storage roll 14, I supply a web of tissue paper 23 to be interposed between the winding of the printed fabric. This web of paper is supplied from the roll 24, which is mounted 95 centrally in the framework, so as to rotate therewith.

As a backing and to provide a proper surface for the plates 4 of the box frame upon which the printing is done, the outer surfaces of these plates are covered with oil-cloth, which prevents the ink from running and also acts as an ink repellent to prevent the ink from passing through the fabric to any extent. Across the upper end of each 100 of the four side plates 4 of the box frame, is a guide bar or straight edge 25, 25, upon which registration marks 26 are indicated, and the tarlatan is passed under these guide bars.

The printing plates, from which the paper impression is taken of the print to be made on the fabric as hereinbefore described, are also provided with the same registration marks.

In order to imprint the web of tarlatan with the desired design in colors, the material is stretched from the supply roll over the four faces of the box frame and to the storage roll as above described. With the box frame in vertical position and with the lock bar 7 engaging the lugs 8, 8, the operator takes the impression sheet of paper and obtaining the proper registration by the marks 26, the sheet with the ink side inward is pressed upon the fabric. The box frame is then unlocked by swinging up the lock bar 7 and the frame given a quarter turn, and a second impression taken from the impression paper, and so on for the four sides of the frame. Sufficient ink is supplied to the impression sheet originally to permit these four impressions to be taken. Then the impression sheet with the next color is impressed in the same way on the fabric, registration being obtained by the marks 26 and the marks on the sheet. This method is pursued for as many color sheets as are desired to be used. After the printing is accomplished for all the colors, the tarlatan web is wound up on the storage roll, and another set of impressions taken.

By the use of the oilcloth backing described above, I am able to print an entire

roll of tarlatan or other fabric, say of two hundred and fifty yards, without cleaning the oilcloth. After each roll of the fabric is printed, however, the oilcloth backing is cleaned, and a new roll mounted in the machine.

Having thus described my invention, what I claim as new, and desire to secure by Letters Patent, is:

1. The process for printing designs in a plurality of colors on desired portions of a continuous strip of tarlatan and material of like properties, which consists in cutting the designs in direct on a suitable flat plate, taking impressions in reverse on a paper sheet in the colors desired, stretching the desired portion of tarlatan over a flat plate, and impressing manually the paper sheets on the fabric to be printed in rotation without changing the position of the tarlatan on the plate.

2. The process for printing designs on desired portions of a continuous strip of tarlatan and material of like properties, which consists in cutting the design on a suitable flat plate, taking an impression in reverse on a paper sheet, stretching the fabric over a flat plate covered with oilcloth or like ink-repellent covering, and impressing manually the paper sheets on the fabric to be printed.

FRANK R. CLARK.
